UNITED STATES PATENT OFFICE

FERDINAND S. BARBIERS, OF LANCASTER, OHIO, ASSIGNOR, BY MESNE ASSIGNMENTS,
TO MARION LAMBERT, INC., OF ST. LOUIS, MISSOURI, A CORPORATION OF MISSOURI

DESIGN FOR A BOTTLE OR SIMILAR CONTAINER

Application filed March 7, 1932. Serial No. 43,109. Term of patent 14 years.

To all whom it may concern:

Be it known that I, FERDINAND S. BARBIERS, a subject of the King of Belgium, residing at Lancaster, in the county of Fairfield and State of Ohio, have invented a new, original, and ornamental Design for a Bottle or Similar Container, of which the following is a specification, reference being had to the accompanying drawing, forming part thereof.

Fig. 1 is a plan view of a bottle or similar container, showing my new design.

Figs. 2 and 3 are elevations of a bottle or similar container showing my new design, the two figures being taken from slightly different viewpoints.

Fig. 4 is a bottom plan of a bottle or similar container as shown in Figures 2 and 3.

I claim:

The ornamental design for a bottle or similar container as shown.

FERDINAND S. BARBIERS.
